UNITED STATES PATENT OFFICE.

WALLACE R. MARIE, OF BRIGHTON, MASSACHUSETTS.

EGG-BEATER.

No. 798,613.

Specification of Letters Patent.

Patented Sept. 5, 1905.

Application filed December 21, 1904. Serial No. 237,756.

To all whom it may concern:

Be it known that I, WALLACE R. MARIE, a citizen of the United States, residing at Brighton, in the county of Suffolk and State of Massachusetts, have invented new and useful Improvements in Egg-Beaters, of which the following is a specification.

This invention relates to an improved egg-beater, the object of the invention being to 10 provide a cheap and simple device, easily manipulated and durable in its construction, which by the exercise of a slight amount of labor will impart a rapid oscillating rotary motion to an agitator which is shaped in such 15 a manner as to thoroughly stir and beat eggs, whip cream, and the like.

The object of the invention is, further, to provide a device so constructed that by rotation of the agitator air will be forced through 20 the liquid, so as to very much lessen the time necessary to thoroughly beat the eggs, whip the cream, or the like.

The invention consists in the combination and arrangement of parts set forth in the following specification and particularly pointed out in the claims thereof.

Referring to the drawings, Figure 1 is a plan view, partly in section, on line 1 1 of Fig. 2 of my improved egg-beater. Fig. 2 is a section, partly in elevation, taken on line 2 2 of Fig. 1. Fig. 3 is a plan view, partly in section, similar to Fig. 1, illustrating a modified form of agitator. Fig. 4 is a section, partly in elevation, taken on line 4 4 of 35 Fig. 3.

Like numerals refer to like parts throughout the several views of the drawings.

In the drawings, 5 is an agitator formed of a plurality of curved sheet-metal arms 6 6, said 40 arms preferably radiating from a common center 7 and having spaces 8 8 therebetween. The outer ends of the arms 7 are joined together for the purpose of giving strength to the structure by a wire 9. Each of the arms 6 is provided with a port 10, said ports being 45 formed by striking up a flange 11 from the material of which said arms are constructed. To each of the arms 6 is attached a tubular aerator 12, by means of which during the rotation of the agitator hereinafter described air is forced through the liquid which is being beaten.

The central portion 7, as will be seen by reference to Fig. 2, forms the lowest portion of

the egg-beater when said egg-beater is placed 55 in a vertical position and constitutes a pivot about which the agitator rotates.

The agitator 5 is fastened to a cylindrical shank 13, and mounted upon said cylindrical shank is a tubular slide 14, movable longitudinally upon said shank, said shank rotatable within said slide. The median lines of the tubular aerators 12 preferably lie in a plane at right angles to the median axial line of the shank 13. A pin 15, fast to said slide 14, projects inwardly therefrom into a helical groove 16, formed upon the periphery of the shank 13. A handle 17 is fast to the upper end of the tube 14, and a spiral spring 18 is located in the upper end of said tube, the upper end 60 of said spring bearing against said handle, the lower end thereof bearing against the upper end of the shank 13.

The general operation of my improved egg-beater is as follows: The agitator 5 is placed 75 in the liquid to be whipped, said liquid preferably contained in a bowl or other appropriate vessel and of a depth sufficient so that said agitator will be entirely submerged therein.

The pivotal center 7 of the agitator rests upon 80 the bottom of the bowl, and the device is held with the shank 13 and slide 14 in a vertical position, as illustrated in Fig. 2. The operator presses downwardly upon the handle 17, compressing the spring 18 and pushing the 85 slide 14 downwardly against the action of said spring 18. The slide 14 and handle 17 are held against rotation by the operator, so that as the pin 15 is carried downwardly by said slide 14 the shank 13 is rotated by said pin in 90 connection with the helical groove 16, formed in said shank 13, and as said shank rotates the agitator 5 as a whole, fast thereto, rotates therewith in one direction, and when pressure is released upon the handle 17 the spring 18, 95 reacting, raises the slide 14 and rotates the shank 13, together with the agitator 5, by means of the pin 15 and groove 16 in the opposite direction. Thus it will be seen that the agitator is rotated alternately in opposite directions by pressing downwardly upon and 100 releasing the handle 17. The curved arms 6 6 passing through the liquid act to beat or whip the same, and this action is still further assisted by the flanges 11, which come in contact with the liquid and guide the same through the ports 10, formed in said arms 6. In addition to the whipping and beating action of 105

the arms 6 and the flanges 11 the aerators 12 form a very important and substantial part in the whipping and beating of the liquid, for said aerators being filled with air as they pass through the liquid force this air through the liquid under pressure and very much accelerate the whipping or beating of the liquid for the purpose of changing said liquid to a frothy consistency, such as whipped cream, eggs for frosting, and the like.

In Fig. 3 a modified form of my invention is illustrated in which the arms 6' 6' of the agitator 5' are formed from strips of sheet metal having substantially parallel sides. Said strips of metal are fast at a common central point to a shank 13', which is rotated by a slide 14', connected thereto by a pin 15', similar to the form illustrated in Figs. 1 and 2 of the drawings, except that in the modified form the slide 14' instead of being a tube is made of a solid cylindrical rod with the handle 17' integral therewith, and this rod may be made of wood to cheapen the construction, the pin 15' being fastened to the rod and projecting into the helical groove 16', formed in the shank 13'. The spring 18' in the modified form is inclosed in the tube 13', the bottom of said spring bearing against the arms 6' at the point where they intersect in the common center 7' and the upper end of said spring bearing against the lower end of the slide 14', the action of the device as a whole in the modified form being substantially the same as that illustrated in Figs. 1 and 2. The difference in construction is principally useful in that waste strips of metal may be used, thus very much reducing the cost of the device as compared with arms of the shape illustrated in Fig. 1 of the drawings, and, further, the slide 14', as hereinbefore stated, being made of a solid cylindrical rod may be formed of wood, if so desired. It is further noted that while in the form illustrated in Figs. 1 and 2 the aerators 12 are each supported upon its respective arm in the form illustrated in Figs. 3 and 4 the aerators 12' extend from one arm 6' to the arm adjacent thereto.

Having thus described my invention, what I claim, and desire by Letters Patent to secure, is—

1. As an article of manufacture, an egg-beater comprising in its construction a shank, an agitator fast to said shank, and an aerator consisting of a hollow tube fast to said agitator, the median line of said aerator lying in a plane substantially at right angles to the median line of said shank.

2. As an article of manufacture, an egg-beater comprising in its construction an agita-

tor formed of a plurality of curved sheet-metal arms with spaces therebetween, tubular aerators fast to said arms, a shank fast to said agitator, a slide mounted to move longitudinally of said shank said shank rotatable on said slide, and means connecting said shank and slide, whereby a rotary motion is imparted to said shank when said slide is moved longitudinally thereof.

3. As an article of manufacture, an egg-beater comprising in its construction an agitator formed of a plurality of curved sheet-metal arms with spaces therebetween, said arms radiating from a common center and said center adapted to form a pivot upon which said agitator rests and about which it is adapted to be rotated, tubular aerators fast to said arms, a shank fast to said agitator, a slide mounted to move longitudinally of said shank, said shank rotatable on said slide, and means connecting said shank and slide, whereby a rotary motion is imparted to said shank when said slide is moved longitudinally thereof.

4. As an article of manufacture, an egg-beater comprising in its construction a cylindrical shank, an agitator fast to said shank, tubular aerators fast to said agitator, the median lines of said aerators located in a plane substantially at right angles to the median axial line of said shank, a tubular slide mounted to move longitudinally of said shank, said shank rotatable on said slide, and a pin fast to said tube and projecting into a helical groove formed in said shank, whereby a rotary motion is imparted to said shank when said slide is moved longitudinally thereof.

5. As an article of manufacture, an egg-beater comprising in its construction a cylindrical shank, an agitator fast to said shank, tubular aerators fast to said agitator, the median lines of said aerators located in a plane substantially at right angles to the median line of said shank, a tubular slide mounted to move longitudinally of said shank, said shank rotatable on said slide, a pin fast to said tube and projecting into a helical groove formed in said shank, a handle fast to the upper end of said tube, and a spiral spring located in said tube between said handle and the upper end of said shank, whereby a rotary motion is imparted to said shank when said slide is moved longitudinally thereof.

In testimony whereof I have hereunto set my hand in presence of two subscribing witnesses.

WALLACE R. MARIE.
